UNITED STATES PATENT OFFICE.

JULIAN L. PERKINS, OF WEST SPRINGFIELD, AND HIRAM D. CROFT, OF SPRINGFIELD, MASSACHUSETTS, ASSIGNORS TO PERKINS MACHINE AND GEAR COMPANY, OF SPRINGFIELD, MASSACHUSETTS, A CORPORATION OF MASSACHUSETTS.

BROACH MECHANISM.

Application filed April 7, 1927. Serial No. 181,843.

Our invention relates to improvements in mechanisms for automatically changing the positions of reciprocating broaches, resides in a reciprocating member, a rotatable broach holder carried by said member locking and releasing means intermittently to impart rotary motion to said holder, rotating means for said holder, means sequentially to operate automatically said locking and releasing means and the holder-rotating means each time said reciprocating member approaches either end of its travel, together with such other parts and members as may be necessary or desirable in order to render the mechanism complete and serviceable in every respect all as hereinafter set forth.

The primary object of our invention is to provide comparatively simple, yet strong, durable, and highly efficient mechanism for automatically operating a holder for two or more broaches or lines of broaches to bring them alternately into broaching position or the cutting field, to the end that the cutting or broaching operation is practically continuous, that is to say, when the broaches or the lines of broaches descend one makes a cut, and when they ascend another makes a cut, and the operation of broaching is thereby materially accelerated, and the production of the machine equipped with our mechanism correspondingly increased.

Another object is to produce a mechanism of this character which is positive and accurate in its operation.

Other objects and advantages will appear in the course of the following description.

This mechanism is designed to be incorporated in broaching machines of the type disclosed in Letters Patent of the United States, No. 1,642,593.

We attain the objects and secure the advantages of our invention by the mechanism illustrated in the accompanying drawings, in which—

Figure 1 is a top plan of broach mechanism which embodies a practical form of our invention, showing the same in connection with the closely associated parts and members of a broaching machine; Fig. 2, a left-hand side elevation of said mechanism and said parts and members, with portions broken out and broken away; Fig. 3, a front elevation of said mechanism, or enough of the same to show the disposition thereof

when the broach holder is at the upper end 55 of its travel; Fig. 4, a similar view showing the disposition of the mechanism when said holder is at the lower end of its travel; Fig. 5, a cross section through portions of said mechanism, taken on lines 5—5, looking 60 down, in Fig. 6, and, Fig. 6 a vertical section through the mechanism, taken on lines 6—6, looking in the direction of the associated arrow, in Fig. 3.

Similar reference characters designate 65 similar parts throughout the several views.

The old parts and members shown in connection herewith as necessary for a complete understanding of the present invention comprise a column 1, a ram 2 arranged to reciprocate vertically on said column, and provided on one side with a rack 3, and a pinion 4 intermeshing with said rack, said pinion being mounted on a shaft 7. From any suitable source of motive power the shaft 7 70 is caused to rotate, and, through the medium of the pinion 4 and the rack 3, to actuate the ram 2 on the column 1. Reversing means for the shaft 7, and means to bring about the operation of said reversing means 75 each time the ram 2 arrives at either end of its travel are required, but these are not shown because the nature of the same is well understood. In this connection, however, reference may be had to the aforesaid 80 patent.

Broaches such as are used in this art are usually made up in sections arranged end to end, so that the separate sections or individual broaches, to all intents and purposes, 90 form one broach, and they will herein be so considered. Two broaches of this character are represented at 8 and 9, respectively, the broach 8 having teeth to cut on the down stroke and the broach 9 having teeth to cut 95 on the up stroke.

A vertical, cylindrical holder 10 is provided for the broaches 8 and 9. This holder has a long trunnion 11 at the top and a short trunnion 12 at the bottom, and said trunnions are journaled in upper and under bearings 13 secured by bolts or other means to the face of the ram 2, said holder fitting between adjacent sides of said bearings.

There are longitudinal slots 14 in opposite 105 sides of the holder 10 to receive the broaches 8 and 9. Each slot 14 also receives, in addition to one of the broaches, abutment blocks

15 at the top and bottom, and an intermediate wedge bar 16. Each broach fits in between the abutment blocks 15 in the slot 14 in which said broach is located, and one of the 5 wedge bars 16 fits into said slot between said blocks above and below and between the broach and one side of said slot, laterally. The broaches 8 and 9 have dove-tailed bodies, and the sides of the slots 14 and of the bars 10 16 which are contiguous with said bodies are undercut to engage the same and hold the broaches securely in place, all in the usual and well known manner. The abutment blocks 15 and the wedge bars 16 are secured 15 in the slots 14 in the holder 10 by screws or other means, so that they can be removed and changed for other blocks and bars needed for broaches of different lengths or widths, or both.

20 An upright 17 is located at the left of the ram 2, has a rearwardly-extending flange 18 that is bolted at 19 to the column 1, and has its lower end bolted at 20 to a fixed part 21 of the frame of the machine. The flange 18 25 is intermediate of the ends of the upright 17. Secured by screws or other means to the inner or right-hand edge of the upright 17 are two fixed cams or dogs 22. The upper end of each dog 22 inclines from the left downwardly to the right, and the lower end of each dog 22 inclines from the left upwardly to the right. Secured by screws or other means to the face of the upright 17 adjacent to its upper end is a cam plate 23, and similarly secured to said face of said upright adjacent to the lower end thereof is a cam plate 24. The bottom end of the cam plate 23 inclines from the right upwardly and outwardly, and the upper end of the cam plate 24 inclines from the right downwardly and outwardly. The upper dog 22 is a short distance below the cam plate 23, and the lower dog 22 is some little distance above the cam plate 24, and the front sides of said dogs 40 and the back sides of said plates are in the same vertical plane. A triangular cam plate 25 is secured by screws or other means to the face of the upright 17 adjacent to the cam plate 23, and a like cam plate 26 is similarly secured to said upright adjacent to the cam plate 24. Adjacent inclined edges of the cam plates 23 and 24 are parallel, so, also are adjacent inclined edges of the cam plates 25 and 26. The outer or left-hand 45 side edges of all of these cam plates are in the same vertical plane. Each of the cam plates 25 and 26 is cut out to accommodate a dog 27 which is pivotally connected at 28 with its plate, and to receive a spring 29. The spring 29 has one end fastened to the cam plate 25 (or 26) and the other end attached to the adjacent end of the dog 27 which is pivoted to said plate, and normally retains said dog with the outer terminal projecting to the left beyond the left-hand edge

of the plate, the dog, when in this normal position, bearing with the aforesaid end against a part of the plate which forms a stop therefor, as represented at 30. When the upper dog is disposed in the aforesaid normal position by the spring 29, the lower end of said dog forms a continuation or is in the same plane with the lower inclined edge of the cam plate 25, and when the lower dog 27 is likewise disposed the upper end 75 of the same forms a continuation of or is in the same plane with the upper inclined edge of the cam plate 26.

Mounted on and secured to the trunnion 11, directly above the upper bearing 13, is 80 a pinion 31. Pivotally connected at 32 with a lug 33 on the hub of the pinion 31 is a pawl 34. Mounted on and secured to the trunnion 11 above the pinion is a lock collar 35. The collar 35 has a flanged part in 85 which are oppositely disposed radial notches 36. The collar 35, below the aforesaid flanged part thereof is serrated to form a ratchet 37 adapted by construction and position to be engaged by the pawl 34. By means of the ratchet 37 and the pawl 34 the collar 35 is prevented from being rotated to the left. A spring 38 has one terminal attached to the lug 33 and the other terminal bears on the pawl 34 in a manner to 90 retain said pawl in engagement with the ratchet 37.

A bar 39 is bolted or otherwise secured to the top of the ram 2, and the front side of said bar is undercut, as represented at 40, to form a guide for a horizontal rack bar 41, said bar being transversely arranged on the top of said ram and extending forwardly onto the top of the holder 10, and projecting to the left beyond the ram. The rack bar 100 41 is provided at the outer end on the back side with a roll 42. The roll 42 is located in position to engage the cam plates 23, 24, 25, and 26, and is of a size which enables the same to pass through the channels between the cam plates 23 and 25, and the channel between the cam plates 24 and 26.

At the left-hand end of the bar 39 is a bracket 43 which extends above the top of said bar. At the top of the bracket 43, 115 and parallel with the plane of the front side of the ram 2, is a socket 44 for a horizontal plunger 45 and a spring 46. Tapped into the outer end of the socket 44 is a plug 47. The plunger 45 has an extension or spindle 120 48 that extends to the left and out through the plug 47. The spring 46 is interposed between the plug 47 and the plunger 45, encircling the spindle 48. The plunger 45 is located by the socket 44 in the same plane 125 with the axis of the collar 35, and is adapted to enter either of the notches 36 in said collar, and thus lock the collar and the parts and members controlled thereby against rotation. In the top and longitudinal center 130

of the socket 44 is a slot 49 extending lengthwise of said socket.

Pivottally connected at 50, intermediate of its ends, with the bracket 43 is a lever 51.

5 The lever 51 is on top of the bracket 43, extends rearwardly from the socket 44, and has therein adjacent to each terminal thereof a longitudinally extending slot 52. The forward terminal of the lever 51 is over the slot 10 49 in the socket 44. A pin 53 has its lower end set in the plunger 45, and extends upwardly through the slot 49 in the socket 44 and the forward slot 52 in the lever 51.

A slot 54 is provided in the bracket 43, 15 back of and parallel with the socket 44, to receive a plunger 55, and a pin 56 extends upwardly therefrom through the rear slot 52 in the lever 51. The plunger 55 is held in place in the slot 54 by means of a plate 57 that is secured by screws or other means to the top of the bracket 43. The plunger 55 is provided at the outer terminal with a roll 58. The roll 58 is positioned by the plunger 55 in the path of the dogs 22.

25 In each bearing 13 is a vertical passage 59 opening through the side of said bearing which is contiguous with the holder 10. A pin 60 and a spring 61 are located in each socket. In each end of the holder 10 are 30 two diametrically opposite recesses to receive the exposed terminal of the contiguous pin 60. In Fig. 3 parts are broken away to show at 62 three of these recesses. The pins 60 and the recesses 62 are so located relative to 35 each other and to the plunger 45 and the notches 36, that said pins hold the bearing 10 against rotation at the time said plunger is momentarily disengaged from the collar 35, as will hereinafter more clearly appear. 40 The springs 61 are between the inner ends of the pins 60 and the inner ends of the passages 59 in the bearings 13, and thus retain said pins in contact with the bearing 10 and in two of the recesses 62 when they are in 45 line with said pins. The springs 61 yield, however, and permit the pins 60 to be forced inwardly when the holder 10 is rotated.

When the parts and members are disposed as shown in Figs. 1, 2, 3, 5, and 6, the broach 8 is located in the cutting field and about to be carried down through the same by the ram 2. The holder 10 is locked with the broach 8 in the position just noted by means of the plunger 45, and the roll 42 is in contact with the left-hand or outer edge of the cam plate 23. Starting with the parts and members thus disposed, the complete operation of the mechanism is described as follows:

50 As the ram 2 descends and the broach 8 makes its cut, the roll 42 is carried with said ram, and on the way, after leaving the outer edge of the cam plate 23, passes in contact with the outer edge of the cam plate 25, encounters the upper dog 27 and momen-

tarily rocks the same on its pivot 28, against the resiliency of the attached spring 29, out of the way, and continues downward until said roll encounters the lower dog 27.

In descending, the ram 2 not only carries 70 downwardly with it the rack bar 41 which is provided with the roll 42, but also the plunger 55 which is provided with the roll 58, and said roll first encounters the upper 75 dog 22 and is reciprocated thereby. The reciprocation of the plunger 55 rocks the lever 51 on its pivot 50, through the medium of the pin 56, first in the direction to withdraw the plunger 45 from engagement with the collar 35, against the resiliency of the spring 80 46, and then in the direction to permit said spring to restore said plunger to engagement with said collar, through the medium of the pin 53. During this momentary release of the collar 35 and therefore of the holder 10, 85 said holder is held against rotation by the pins 60 which are in two of the recesses 62. As the ram 2 continues on its downward course, and after the broach 8 has completed its cut, the roll 58 encounters the lower dog 90 22 and momentarily unlocks the holder 10 in the manner just described, and during this time the roll 42, having arrived at the lower dog 27, rides downwardly and inwardly on said dog and on the cam plate 26 until said roll passes off of said plate into the channel between the same and the cam plate 24. In moving inwardly the roll 42 carries with it the rack bar 41 and one-half of a revolution to the right is imparted to the holder 10, 95 through the medium of said bar, the pinion 31, and the pawl 34, whereby the broach 8 is moved out of and the broach 9 is moved into the cutting field. When the half revolution is thus imparted to the holder 10, it 100 forces downwardly the pins 60, against the resiliency of the springs 61, until the other two recesses 62 are brought into line with said pins, when said springs force said pins into said recesses. 110

The roll 42 is carried downwardly and outwardly through the channel between the cam plates 24 and 26, by the ram 2 in its further downward movement, until said roll bears against the left-hand or outer edge of 115 said first-named cam plate, as shown in Fig. 4. The rack bar 41 is thus actuated outwardly again, and imparts one-half of a revolution to the pinion 31 in the opposite direction to which said pinion was previously 120 actuated, but this time the movement is not transmitted to the holder 10, because the pawl 34 passes idly over the ratchet 37. Before the roll 42 enters the channel between the cam plates 24 and 26, the roll 58 clears 125 the dog 22, and the holder 10 is locked by the plunger 45, said plunger this time being in the notch 36 that is opposite to that in which said plunger was first located.

The general disposition of the mechanism 130

now corresponds with that illustrated in Fig. 4.

As soon as the roll 42 rides onto the outer edge of the cam plate 24, the direction of the ram is changed, and said ram commences to ascend. In ascending the ram carries the rack bar 41 and the plunger 55 upwardly, the roll 42 passes from the outer edge of the cam plate 24 to the outer edge of the cam plate 26, rocks the lower dog 27 out of the way and continues upwardly until it arrives at the upper dog 27. Meanwhile the roll 58 encounters the lower dog 22 and momentarily unlocks the holder 10, but the same is held against rotation by the pins 60. By the time the roll 42 encounters the upper dog 27, the roll 58 has encountered the upper dog 22, and the broach 9 has completed its cut. The roll 58 in passing over the upper dog 22 brings about the unlocking of the holder 10, and the roll 42 rides upwardly and inwardly on the end of the upper dog 27 and the aligning edge of the cam plate 25. In moving inwardly the roll 42 again actuates the rack bar 41 inwardly and in the direction to cause to be imparted another half revolution to the holder 10, whereby the broach 9 is moved out of and the broach 8 is again moved into the cutting field, and the holder 10 is relocked as soon as the roll 58 rides off of the upper dog 22. The roll 42, in passing into the channel between the cam plates 23 and 25 and through the same onto the outer edge of said first-named cam plate, carries the rack bar 41 outwardly again, but the pawl 34 clicks over the ratchet 37 and the holder 10 is not affected. The mechanism is now ready for the next and immediately following cycle.

40 The face of the ram 2 is recessed, as shown at 63, to accommodate each broach when located in its inactive position.

Although we have illustrated and described mechanism for two broaches, it is obvious that the same might be constructed to carry and operate more than two broaches, and this without making any change, either structurally or functionally, which would materially affect the invention.

50 More or less change in the shape, size, construction, and arrangement of some or all of the parts of this mechanism in addition to those hereinbefore directly or indirectly noted, may be made, without departing from the spirit of our invention, or exceeding the scope of what is claimed.

What we claim as our invention, and desire to secure by Letters Patent, is—

1. In mechanism of the class described, a reciprocating member, a broach holder carried by said member and rotatable thereon in one direction only, and automatic means intermittently to rotate said holder.

2. In mechanism of the class described,

a reciprocating member, a broach holder carried by said member and rotatable thereon in one direction only, means to lock and release said holder, and means partially to rotate said holder while unlocked.

3. In mechanism of the class described, a reciprocating member, a broach holder carried by said member and rotatable thereon in one direction only, yielding means normally retaining said holder against rotation, and intermittently operating means partially to rotate said holder.

4. In mechanism of the class described, a reciprocating member, a broach holder carried by said member and rotatable thereon in one direction only, means positively to lock said holder against rotation, intermittently operating means to actuate said locking means out of locking position, and intermittently operating means partially to rotate said holder, when unlocked against the resistance of said yielding means.

5. In mechanism of the class described, a reciprocating member, a broach holder carried by said member and rotatable thereon in one direction only, yielding means preventing said holder from rotating, means positively to lock said holder against rotation, intermittently operating means to actuate said locking means out of locking position, and intermittently operating means partially to rotate said holder, when unlocked, against the resistance of said yielding means.

6. In mechanism of the class described, a reciprocating member, a rotatable broach holder carried by said member, means to actuate said holder on its axis in one direction only, and means to cause said actuating means to operate each time said reciprocating member approaches either end of its travel.

7. In mechanism of the class described, a reciprocating member, a rotatable broach holder carried by said member, reciprocating means adapted to impart a rotary motion to said holder in one direction, when said reciprocating means is actuated in one direction, and means to prevent said reciprocating means, when moved in the opposite direction, from acting on said holder.

8. The combination, in mechanism of the class described, with a reciprocating member provided with a rack bar having a projection, and cam plates in the path of said projection adjacent to each end of the movement imparted thereto by said reciprocating member, whereby said projection is moved to reciprocate said bar, of a broach holder mounted on said reciprocating member, and provided with a pinion which intermeshes with said rack bar.

9. The combination, in mechanism of the class described, with a reciprocating mem-

ber, two plungers operatively connected by a lever, one of said plungers having a projection, and dogs in the path of said projection, whereby, when said projection encounters said dogs, said plungers are actuated, of a broach holder rotatably mounted on said member, and provided with a notched collar adapted to be engaged by and released from the other of said plungers, and means to impart rotary motion to said holder each time said reciprocating member approaches either end of its travel.

10. The combination, in mechanism of the class described, with a reciprocating member provided with a rack bar having a projection, and two cam plates in the path of said projection adjacent to each end of the movement imparted thereto by said reciprocating member, certain of said cam plates being provided with yielding dogs each of which permits said projection to move in one direction in a straight line, but diverting from said line said projection when moved in the opposite direction, whereby said projection is moved to reciprocate said bar, of a broach holder mounted on said reciprocating member, and provided with a pinion which intermeshes with said rack bar.

11. The combination, in mechanism of the class described, with a reciprocating member provided with a rack bar having a projection, and two cam plates in the path of said projection adjacent to each end of the movement imparted thereto by said reciprocating member, certain of said cam plates being provided with yielding dogs each of which permits said projection to move in a straight line in one direction, but diverts from said line said projection when moved in the other direction, whereby said projection is moved to reciprocate said bar, of a broach holder mounted on said reciprocating member, and provided with a pinion which intermeshes with said rack bar, and

45 bar to be returned to operative position without affecting said holder.

12. The combination, in mechanism of the class described, with a reciprocating member provided with a rack bar having a projection, and two cam plates in the path of said projection adjacent to each end of the movement imparted thereto by said reciprocating member, certain of said cam plates being provided with yielding dogs each of 50 which permits said projection to move in a straight line in one direction, but diverts from said line said projection when moved in the other direction, whereby said projection is moved to reciprocate said bar, of a 55 broach holder mounted on said reciprocating member, and provided with a pinion which intermeshes with said rack bar, and with a ratchet and pawl to enable said rack bar to be returned to operative position without 60 affecting said holder, and yielding means normally to prevent said holder from rotating.

13. The combination, in mechanism of the class described, with a reciprocating member provided with a reciprocating rack bar having a projection, cam members in the path of said projection at either end of the movement imparted thereto by said reciprocating member, whereby, when said projection encounters said cam members, said rack is actuated, two plungers operatively connected by a lever, one of said plungers having a projection, and dogs in the path of said last-named projection, whereby, when 70 said last-named projection encounters said dogs, said plungers are actuated, of a broach holder rotatably mounted on said member, and provided with a pinion which intermeshes with said rack bar, and further provided with a notched collar adapted to be 75 engaged by and released from the other of said plungers.

JULIAN L. PERKINS.
HIRAM D. CROFT.
